US00D888505S

(12) **United States Design Patent** (10) **Patent No.:** **US D888,505 S**
(45) **Date of Patent:** **** Jun. 30, 2020**

(54) **BEVERAGE HOLDER**

(71) Applicant: **YETI Coolers, LLC**, Austin, TX (US)

(72) Inventors: **Roy Joseph Seiders**, Austin, TX (US);
John Alan Tolman, Austin, TX (US)

(73) Assignee: **YETI Coolers, LLC**, Austin, TX (US)

(**) Term: **15 Years**

(21) Appl. No.: **29/664,317**

(22) Filed: **Sep. 24, 2018**

Related U.S. Application Data

(63) Continuation of application No. 29/596,829, filed on Mar. 10, 2017, now Pat. No. Des. 829,058, which is a continuation of application No. 29/581,483, filed on Oct. 19, 2016, now Pat. No. Des. 826,003, which is a continuation of application No. 29/540,989, filed on Sep. 29, 2015, now Pat. No. Des. 780,531, which is a continuation of application No. 29/500,908, filed on Aug. 29, 2014, now Pat. No. Des. 752,397.

(57) **CLAIM**

The ornamental design for a beverage holder, as shown and described.

DESCRIPTION

FIG. 1 is a top, front, left perspective view of a beverage holder showing our new design;

FIG. 2 is a front view thereof;

FIG. 3 is a right side view thereof;

FIG. 4 is a rear view thereof;

FIG. 5 is a left side view thereof; and,

FIG. 6 is a top view thereof.

The broken lines showing the remainder of the beverage holder are for environmental purposes only and form no part of the claimed design.

1 Claim, 4 Drawing Sheets
